UNITED STATES PATENT OFFICE.

JOHN L. PORTER, OF ST. LOUIS, MISSOURI.

WEATHER-STRIP.

No. 921,159.

Specification of Letters Patent.

Patented May 11, 1909.

Application filed April 3, 1908. Serial No. 425,023.

To all whom it may concern:

Be it known that I, JOHN L. PORTER, a citizen of the United States, residing in the city of St. Louis and State of Missouri, have 5 invented new and useful Improvements in Weather-Strips, of which the following is a specification.

This invention relates to certain new and useful improvements in weather strips of a 10 type adapted for application in various connections, but intended more particularly for use on the bottom of a door. When so placed it will, when the door is closed, rest upon the door-sill and prevent air from entering beneath the door.

The invention has for its object in addition to the general novelty and simplicity of the construction, to provide a weather strip which may be readily secured on the lower 20 edge of the door and which when so positioned will in operation automatically adapt itself to any unevenness in the door-sill in such manner as to be in contact with the door-sill throughout its length and thereby 25 effectively shut off the passage of air beneath the door.

In the drawing: Figure 1 is a perspective view of the weather strip detached from the door; Fig. 2 is a front view of a portion of a 30 door with my invention applied thereto, the door being closed and partly broken away, and the strip resting upon the door-sill beneath the door, said view being intended to illustrate the manner in which the strip will 35 conform to the uneven surface of the door-sill; and Fig. 3 is a cross section through the lower portion of a door having my invention applied thereto.

Referring now to the drawing, the numeral 40 1 indicates the door, in the lower edge of which near the inner side of the door, is provided a longitudinal groove 2, which extends from side to side of the door. If preferred, however, said groove could stop short of the 45 extreme edges of the door as will be obvious without illustration.

3 indicates a spring-metal strip which is secured along one side to the bottom edge of the door, near the outer side of the latter, 50 from which line of connection it extends downward from the said lower edge of the door. The opposite edge portion of this strip is suitably bent, as shown, to provide a longitudinal recess 4, extending throughout 55 the length of the strip, said recess having substantially parallel walls, and the lower

edge portion of the outer wall being provided throughout its length with a spring-metal wire 5, the material of said wall being simply bent or curled around said wire to incase the 60 same. This wire materially assists in affording a springy character to the free edge portion of the strip to enable it to readily accommodate itself to the shape of the door-sill while at the same time insuring the return of the strip to its normal shape when the door is opened, so that the edge of the strip may not lose its springy character and will at all times press into contact with the door-sill. In order to permit the bearing 65 surface of the strip to yield or bend at different points throughout its length I provide at suitable intervals throughout the strip slits 6, which are cut through both walls of the pocket 4, and which extend from the top 70 of said pocket to near the lower edges of the same. By bending the metal strip 3 to form the pocket 4, an upward projection 7 is provided which is received into the groove 2 in the lower edge of the door, before referred 75 to, and which projection works in said groove 80 as the door is opened and closed.

As is well known, the central portion of a door-sill is subjected to the greatest wear, due to the passing over of persons entering 85 through the door and inadvertently scraping the door-sill with their shoes. If the weather strip extended parallel to the lower edge of the door at all times, it is apparent that there would be a space at the central 90 portion of the door which would not be closed by the weather strip. By reference to Fig. 2, it will be seen that, under the circumstances alluded to above, the central portion of my improved weather strip will 95 project downward into the portion of the door-sill worn away, and that it will be pushed upward into the groove in the door more and more as the sides of the door are approached, until at the extreme ends of 100 the strip its edge will be substantially flush with the lower end of the door.

In order to provide a suitable cushioning effect to the strip and also to render its operation noiseless, I secure in the pocket 4 105 a strip 8, which may be of felt, or rubber, or other suitable material, and which projects below the edge of the strip 3 a sufficient distance to form the actual contact surface of the weather strip.

As indicated above, my invention is not limited in application to a door, or to the

bottom of a door, but may be applied to the appropriate edge, or edges, of windows, or screen-doors, and, in fact to any analogous device co-operating with a surrounding frame 5 to effect a closure, and whether swinging vertically or horizontally.

I claim:

1. In combination with a closure having a longitudinal groove in one edge thereof, a 10 spring-metal plate secured along one of its sides to said edge and having at its opposite side an angular extension forming a pocket, and adapted to work in said groove, and bearing material secured in said pocket 15 and projecting beyond the outer face of said plate.

2. In combination with a door provided with a longitudinal groove in its lower edge, a spring-metal strip secured along one of 20 its sides to said lower edge of the door near one side of the latter and provided in its opposite side portion with an upward extension adapted to work in said groove, said upward extension forming a pocket, and 25 bearing material secured in said pocket and projecting below the lower face of said metal strip.

3. In combination with a door provided in its lower edge with a longitudinal groove, 30 a spring-metal strip secured along one of its sides to said lower edge of the door near one side of the latter and provided at its opposite side portion with an upward extension adapted to work in said groove and 35 forming a pocket extending throughout the length of the strip, bearing material secured in said pocket and projecting below the lower face of said strip, said projecting portion being provided throughout its length 40 at suitable intervals with vertically disposed slits.

4. In combination with a door provided in its lower edge with a longitudinal groove, a spring-metal strip secured along one of 45 its sides to said lower edge of the door near one side of the latter and provided at its opposite side portion with an upward extension adapted to work in said groove and forming a pocket extending throughout the 50 length of the strip, bearing material secured in said pocket and projecting below the

lower face of said strip, said projecting portion being provided throughout its length at suitable intervals with vertically disposed slits, and a spring-metal reinforcing wire 55 secured in the lower edge of the outer wall of said pocket.

5. In combination with a door provided in its lower edge with a longitudinal groove, a spring-metal strip secured along one of 60 its sides to said lower edge of the door near one side of the latter and projecting downward from the surface of the lower edge of the door from such line of attachment thereto, said metal strip having its opposite 65 side portion suitably bent to provide an upward extension working in said groove and having substantially parallel walls providing a pocket, and a strip of felt or the like secured in said pocket and projecting 70 below the lower surface of said metal strip.

6. A weather strip comprising a spring-metal plate having one of its side portions bent upon itself in three directions to provide a longitudinal recess, having substantially parallel walls extending at right angles to the body of the strip and bearing material secured in said recess and projecting 75 beyond the face of said plate.

7. A weather strip comprising a spring- 80 metal plate having one of its side portions bent upon itself to provide a longitudinal recess, the walls of said recess being slit at intervals throughout their length, and bearing material secured in said recess and projecting beyond the face of said plate.

8. A weather strip comprising a spring-metal plate having one of its side portions bent upon itself to provide a longitudinal recess, the walls of said recess being slit at 90 intervals throughout their length, a length of spring wire secured along the edge of the outer wall, and bearing material secured in said recess and projecting beyond the face of said plate.

In testimony whereof I have hereunto set my hand in presence of two subscribing witnesses.

JOHN L. PORTER.
